UNITED STATES PATENT OFFICE.

PETER KASS, OF CHICAGO, ILLINOIS, ASSIGNOR OF ONE-THIRD TO EDWARD BRITTAINE
AND ONE-THIRD TO JULIUS J. ACKER, BOTH OF CHICAGO, ILLINOIS.

UPPER BUFFER FOR VESTIBULE-CARS.

1,397,588.

Specification of Letters Patent.

Patented Nov. 22, 1921.

Application filed July 27, 1921. Serial No. 437,825.

To all whom it may concern:

Be it known that I, PETER KASS, a citizen of the United States, residing at Chicago, in the county of Cook and State of Illinois, 5 have invented certain new and useful Improvements in Upper Buffers for Vestibule-Cars, of which the following is a specification.

This invention relates to vestibule construction for railway cars but more particularly to buffers for the same and has for its primary object to provide a simple, compact and durable spring support for the upper portion of the vestibule face plate.

10 Further objects are to provide a simple form of adjustment for the parts, to facilitate the attachment of the bellows and prevent subsequent injury thereto, to procure greater freedom of action, to provide a construction which is not affected by accumulations of dust and cinders, to eliminate the necessity for the cutting of holes through the ends of the car which permit dirt, moisture and snow to enter the car vestibule in addition to weakening the vestibule structure, to facilitate repair and inspection, to prevent rattling of the parts, to permit vertical as well as horizontal relative movement of the cars, and in general to provide a new and 25 improved buffer.

The many other objects and advantages of the invention will be better understood by reference to the accompanying specification when considered in connection with the accompanying drawing illustrating a selected embodiment thereof, in which:—

30 Figure 1 is a plan view of a portion of a car end equipped with my improved buffer construction.

Fig. 2 is a partial end elevation of the structure shown in Fig. 1.

Fig. 3 is a detail plan view of one of the buffer springs and its support, and

Fig. 4 is a detail view.

45 Referring to the drawing, the usual face plate 10 is connected along its top and sides with the end frame 11 of the car vestibule by an extensible hood or bellows 12 of the usual heavy fabric. This hood is yieldingly held in its extended position by upper and lower buffers but the present invention relates solely to an improved form of upper buffer.

50 The buffer comprises a plate 14 secured on the inner face of the plate 10 above the top

15 of the hood 12 and connected by a pair of yielding members 16 with the end frame 11 of the car. As these members 16 are substantially identical in form, only one will be described in detail as this description will 60 apply equally to the other.

The member 16 consists of a rigid link 17 having its outer end pivotally connected at 18 to lugs 19 on the plate 14 and its inner end similarly connected at 20 to the inner 65 end of a spring-pressed rod or plunger 21 slidably and revolvably mounted in a bracket 22 secured upon the outer face of the frame 11. This bracket comprises an elongated plate having oppositely disposed end flanges 70 23 and 24 provided with perforations in axial alinement to receive and form a support for the plunger 21. A sleeve 25 is preferably formed on or attached to the outer face of the flange 23 to provide a substantial bearing for this plunger.

The plunger 21 is preferably cylindrical and consists of a main portion 26 and a reduced outer portion 27. A flattened head 28 is formed on the inner end of the plunger 80 80 and the link 17 is pivotally connected to this head. A shoulder 29 is formed at the junction of the portions 26 and 27 of the plunger and a washer 30 fits on the reduced portion of the plunger and abuts this shoulder. 85 A coil spring 31 envelops the reduced portion of the plunger and acts between the inner face of the washer 30 and the opposing face of the flange 24 to yieldingly maintain the plunger in its extended position. Cylindrical projections 24' and 30' are preferably formed on the opposing faces of the flange 24 and washer 30 respectively to fit within the corresponding end coils of the spring 31 and maintain the axis of this spring substantially coincident with the axis of the plunger. 90

The outer end of the plunger 21 is preferably threaded to receive a nut 32. Any suitable form of locking means may be used to retain this nut on the plunger. As the 100 spring 31 becomes weakened by long use, the spring pressure may be increased by placing one or more washers 33 upon the plunger, as indicated in Fig. 3. Any suitable form of housing may be provided to inclose the 105 spring 31, as will be readily evident. The bracket 22 may be extended to form a guide or support 22' for the head 28, although this is unnecessary when a plunger of adequate dimensions is used.

The rigid link 17 is preferably formed in two parts connected by a turnbuckle 35 to permit adjustment of the length of the link, though a single piece rod or bar may be used, as will be readily appreciated. The fully extended position of the buffer is shown in solid lines in Fig. 1 of the drawing and the extreme contracted position is indicated in dot, though it would very rarely occur that the buffer would be compressed to this extent.

It is particularly advantageous that the inner ends of the buffer be connected to the end plate of the car as this plate is generally made of heavy steel and provides a firm base for the bracket. In order to permit such a connection, it is necessary that the buffer construction be very compact and the device forming the present invention fully possesses this quality. Heretofore in buffers of this type, the spring rods have generally been connected to the car frame at the inner end of the platform rather than to the frame at the outer end because of the necessary length of these rods and the angle at which they must be set to provide proper action. This has necessitated holes through the end frames which admit dirt to the platform and weaken these frames.

I have found my buffer of material assistance when installing a hood on a car. The inner end of the hood is usually fastened to the end of the car first and it is then extremely difficult, on account of the stiffness of the fabric, to stretch the hood sufficiently to bring the outer end into the proper position for attachment to the face plate and to maintain it in this position until such attachment is completed. I draw the face plate toward the end of the car sufficiently to make the connection easy by engaging the outer ends of the plungers 21 and pulling them outwardly. The plungers may be blocked in this position until the hood is attached.

My buffer is entirely outside the hood and is spaced above the same sufficiently so that the hood cannot be damaged by the movement of the buffer. In modern cars the end frames are practically flat so that the brackets may be attached directly upon these frames in the manner described but when the buffer is to be installed on cars having a rounded end, filler blocks 38 of proper form may be interposed between the bracket and the face plate, as indicated in Fig. 4 of the drawing.

The rod or plunger 21 is preferably round so that it may rotate in the bracket and thus permit relative vertical as well as horizontal movement of the cars. The spring 31 is preferably constantly under slight tension which prevents rattling of the parts.

This tension may be adjusted in the manner described. The position of the buffer

above the hood and wholly outside the vestibule greatly facilitates inspection and repair.

I am aware that many changes may be made in the construction and arrangement of parts and I reserve the right to make all such as fairly fall within the scope of the following claims.

I claim as my invention:

1. In a railway car, the combination with a car frame, a diaphragm face plate movable toward and from said frame, and a hood connecting said plate and said frame, of a buffer between said frame and said plate above said hood comprising a bracket mounted on said frame, a spring controlled plunger slidable in said bracket, and a link connecting said plunger and said face plate and movable in a substantially horizontal plane.

2. In a railway car, the combination with a car frame, a diaphragm face plate movable toward and from said frame, and a flexible hood connecting said plate and said frame, of a buffer between said frame and said plate movable in a path wholly without said hood, said buffer comprising a bracket mounted on said frame, a spring controlled plunger slidable in said bracket, and a link connecting said plunger with said plate.

3. In a railway car, the combination with a frame member, a plate member movable toward and from said frame member, and a hood connecting said members, of a buffer between said members above said hood comprising a bracket mounted on one of said members, a spring-pressed plunger slidable substantially horizontally in said bracket, and a link connecting one end of said plunger with the other of said members and adapted to be moved in substantially a horizontal plane by the relative movement of said members.

4. In a railway car, the combination with a car frame, a diaphragm face plate movable toward and from said frame, and an extensible hood interposed between said frame and said plate, of a buffer between said plate and said frame comprising a bracket on said frame, a spring-pressed rod slidably mounted in said bracket, and a link connecting one end of said rod with said face plate.

5. In a railway car, the combination with a car frame, a diaphragm face plate movable toward and from said frame, and a hood connecting said frame and said plate, of a buffer between said frame and said plate comprising a bracket mounted on said frame, a spring-pressed plunger slidable in said bracket, means for adjusting the spring pressure on said plunger, and a link connecting said plunger with said plate.

6. In a railway car, the combination with a car frame, a diaphragm face plate movable

toward and from said frame, and a hood connecting said frame and said plate, of a buffer between said frame and said plate comprising a bracket on said frame, a 5 spring-pressed plunger slidably and revolubly mounted in oppositely disposed bearings in said bracket, and a link connecting said plunger with said plate.

7. In a railway car, the combination with 10 a car frame, a diaphragm face plate movable toward and from said frame, and a hood connecting said frame and said plate, of a buffer between said frame and said plate comprising a spring-pressed plunger 15 slidably mounted on said frame, a link connecting the end of said plunger with said

plate, and means for adjusting the length of said link.

8. In a railway car, the combination with 20 a car frame, a diaphragm face plate movable toward and from said frame, and a hood connecting said frame and said plate, of a buffer between said frame and said plate comprising a bracket provided with a 25 pair of bearings in axial alinement, a spring-pressed plunger slidable and revoluble in said bearings, means for adjusting the pressure of the spring on said plunger, a link connecting one end of said plunger with said plate, and means for adjusting the length of 30 said link.

PETER KASS.
